UNITED STATES PATENT OFFICE

2,357,265

UNDERCLEARER ROLL

Noah E. Lucas, Norwich, Conn., assignor to Noah Lucas, New Britain, Conn.

Application July 9, 1941, Serial No. 401,621

5 Claims. (Cl. 19—140)

My invention relates to the class of devices above mentioned, and an object of my invention, among others, is the production of an underclearer roll that shall maintain its shape under all conditions to which it is subjected in use; and a further object of the invention is the production of a device of this type that may be readily produced in a comparatively simple manner and that will be particularly effective in the results produced by its operation.

Forms of underclearer rolls embodying my invention and in the construction and use of which the objects herein set out, as well as others, may be attained are illustrated in the accompanying drawing, in which—

Figure 1 is a side view of an underclearer roll embodying my invention.

Figure 2 is a view in central lengthwise section of one end of the roll showing the manner of wrapping.

Figure 3 is an end view of the same.

Figure 4 is a view similar to Fig. 2 but illustrating a little different structure.

Figure 5 is an end view of the latter form of roll.

Figure 6 is a view in central lengthwise section of one end of my underclearer roll embodying a little different form of construction.

Figure 7 is a view similar to Fig. 6 but illustrating another modification.

Figure 8 is an isometric view of one end of the roll illustrated in Fig. 7.

Figure 9 is a view similar to Fig. 8 and illustrating the manner of applying the Cellophane wrapper.

Figure 10 is a view similar to Fig. 7 but illustrating a modification.

Figure 11 is a view illustrating the manner of forming the outer covering from an extension of the paper wrapper only wound several times around the roll to complete the outer jacket.

Owing to the difficulty in showing the sheets, in section, due to the thickness of said sheets, they are not separately shown in the sectional views herein or in the end view, but it will be understood that as otherwise shown in the figures the sheets lie one against the other and are wound several times around the roll to comprise the parts specifically referred to.

The extreme conditions as to heat and moisture in the rooms in which underclearer rolls are used are such as to strain the ability of the rolls to withstand the harmful effects and unless such rolls are most efficiently constructed and in a

manner involving considerable expense their period of operation is short. It is particularly essential that the rolls shall preserve their true form and shape in order to prevent any spaces between them and the rolls in connection with which they are used. It is therefore essential that the underclearer rolls shall be most rigid and that their rigidity shall be preserved, and my invention illustrated and described herein enables rolls bearing these characteristics to be obtained at comparatively little expense.

Up to the present time it has been the universal custom to employ underclearer rolls made of substances and in a manner to withstand to a certain degree the harmful effects of heat combined with moisture hereinbefore referred to. The construction of such rolls has involved considerable expense and it has not been appreciated that the life of such rolls could be materially prolonged. This appears to have been a case in which, as in some other arts, the rolls in use were all sufficient and no thought has been given to any improvement, doubtless from the fact that no improvement was thought to be possible or necessary. No attempt has heretofore been made to improve the structures particularly by protecting the rolls from contact with moisture by the use of an ensheathing material whereby such moisture is prevented from gaining entrance to the material composing the core of the roll.

I have demonstrated that by the use of such an encasing material cheap substances such as wood of an inferior grade and other substances may be employed and when encased in a material impervious to moisture such rolls may be used indefinitely and for periods much longer than the more expensive rolls now in common use, and while preferably I employ Cellophane as a covering or ensheathing material other substances which would be impervious to moisture will be found to accomplish my purpose.

In order to effect my purpose in the production of a roll involving comparatively little expense wood is found to particularly fulfill the requirements, although other material may be employed and the invention will be found to well apply to such rolls. My invention enables such materials to be used without being affected by the extreme heat combined with moisture conditions of the rooms in which they are used, the rolls being encased in a manner to prevent the moisture from gaining access to the bodies or cores of the rolls while the surfaces are maintained in a most sat-

isfactory condition to catch up the lint, threads, etc. which is the purpose of their use.

In the accompanying drawing, referring to Figs. 1 to 3, the numeral 7 denotes the body or core of the roll which in this form is composed of wood of any suitable kind. This body is turned round and true to form and of the required length and diameter for the particular use in connection with which it may be employed.

My invention contemplates the complete enveloping of the body or core 7 in a sheath composed in whole or in part of Cellophane or other material or materials impervious to moisture. In the particular arrangement shown in Figs. 2 and 3 this sheath is composed of several sheets of Cellophane and paper, one sheet of each of said materials being shown for the purpose of illustration herein, said sheets being placed in contact one with the other and then wound upon the roll. While the exact arrangement is not material, as shown the sheet 8 of Cellophane is placed next to the roll 7 at the beginning of the winding operation and the sheet 9 of paper is placed next to the Cellophane sheet as shown in Fig. 2, it being desirable that the sheet 8 of Cellophane shall extend at least once completely around the roll and as many more times as may seem expedient. The two sheets wound together as just explained comprise a sheath 10 which encloses the rolls 7 and this sheath is enclosed in a jacket 11 which may be composed of a separately formed tube of paper or other similar material, or this jacket may be formed by making the paper sheet longer than the Cellophane sheet and winding it several times, independently of the Cellophane sheet, around the roll to complete its formation as hereinbefore shown and described.

To protect the end of the body 7 from the entrance of moisture a cap 12 of material impervious to moisture, as vulcanized rubber or metal, is fitted over the end of the core 7 and has a flange which is extended inwardly to penetrate the end of the sheath and jacket, as shown in Fig. 2 wherein it is forcefully entered between the jacket 11 and the core 7 and into contact with the end of the sheet 10. This cap may be provided with ribs 13 to prevent the cap from turning and a journal 14 comprising the end of a pin 15 driven into the end of the core 7 is provided for the purpose of rotatably mounting the roll in suitable bearings therefor in a manner that will be readily understood.

In that form of the device shown in Figs. 4 and 5 the body or core 16 of the roll is composed of paper formed in any suitable manner, as by winding a sheet or sheets several times around the structure to obtain the desired thickness, or it may be formed in any manner common to the way of making paper rolls. This structure is similar to that shown in Fig. 2 with the exception that the core 16 is formed with recesses 17 in its ends, a plug 18, preferably of wood or similar material, being secured in said recess. The pin 15, journal 14, and cap 12 may be of the same nature as that shown in Figs. 2 and 3 and the structure is enclosed in a jacket 11 as shown in said figures.

In the roll as shown in Fig. 6 the core or body 7, the sheath 10, and pin 15, journal 14 and jacket 11 are formed in substantially the same manner as described and shown with respect to Figs. 2 and 3. A flange 19 is formed on the pin 15 in a manner similar to that shown in Figs. 2 and 4, this flange abutting squarely against a filling 20 which may be composed of glue, shellac,

or other material impervious to moisture this to protect the end of the body or core 7, in a manner that will be readily understood. The device shown in Fig. 7 is similar to that shown in Fig. 6 with the exception that the end of the sheath 10 which is composed of paper and Cellophane, or even of Cellophane alone, is folded over the end of the core as at 21 to complete the sheath 10 and thereby protect the core as particularly shown in Fig. 8.

The structure shown in Fig. 10 is quite similar to that disclosed in Fig. 6 with the exception that the entire jacket 22 is composed of a winding of sheets of Cellophane and paper, as hereinbefore described, and a filling 23 of glue, shellac or similar material impervious to moisture is interposed between the end of the body 7 and the flange 19 on the pin 15.

In that form of the structure shown in Fig. 11 the body or core 7 is enclosed in a sheath 10 formed of a winding of sheets of Cellophane 8 and paper 9 and the jacket 11 is formed by several windings of the sheet 9 of paper which is made considerably longer than the sheet or sheets of Cellophane so that as the Cellophane sheets terminate within the paper winding the latter is continued and wound several times around the roll to complete the jacket 11 as hereinbefore explained in connection with Fig. 2. It is to be noted that the core 7 whether of wood or other material is so enclosed within the jacket comprising the Cellophane and other material that the core may be removed when it has outlived its purpose and a new core substituted, thus enabling the jacket to be used indefinitely.

In accordance with the provisions of the patent statutes I have described the principles of operation of my invention, together with the device which I now consider to represent the best embodiment thereof, but I desire to have it understood that the device shown is only illustrative and that the invention may be carried out by other means and applied to uses other than those above set out.

I claim:

1. An underclearer roll including a body, a sheath including a sheet of Cellophane wrapped several times around the body in tight contact therewith to prevent entrance of moisture thereto, a cap composed of a material impervious to moisture secured to the end of the roll, and a flange on said cap penetrating the end of said sheath in a position spaced from said body.

2. An underclearer roll including a body, a sheath composed of sheets of Cellophane and paper or similar material superimposed and wrapped several times tightly around the body to protect the latter from the entrance of moisture, a cap secured to the end of the roll, and a flange on said cap penetrating the end of said sheath in a position spaced from said body.

3. An underclearer roll including a body, a sheath enclosing said body and formed of sheets of Cellophane and paper or similar material wrapped about said body to protect it from entrance of moisture, the sheet of paper being extended beyond the Cellophane wrapping to comprise a jacket for said roll, and means for securing the end of the roll with material impervious to moisture to prevent entrance of moisture to the core of the roll.

4. An underclearer roll including a body, a sealing case including a sheet of Cellophane and a sheet of paper superimposed and wrapped tightly about the roll in sealing contact there-

with, the sheet of Cellophane being next to the body and the sheet of paper being longer than the sheet of Cellophane to extend beyond the latter in wrapping around the core, and means ensealingly engaged with the ends of said case for sealing the end of the roll to prevent access of moisture to said body.

5. An underclearer roll including a body, a sealing case including a sheet of material impervious

to moisture wrapped about said body in tight contact therewith to form an ensealing sheath therefor, a cap composed of a material impervious to moisture secured to the end of the roll, and a flange on said cap ensealingly penetrating the end of said sheath to prevent entrance of moisture to said sheath, said flange being spaced from said body.

NOAH E. LUCAS.
